TRAFFIC SIGNALING SYSTEM

Harry E. Hershey, Chicago, Ill., assignor to Associated Electric Laboratories, Inc., Chicago, Ill., a corporation of Delaware

Application March 14, 1938, Serial No. 195,772

21 Claims. (Cl. 246—130)

The present invention relates to traffic signaling systems, and more particularly to improvements in railway crossing signaling systems, wherein a highway signal located near the intersection of a stretch of railway track and a highway is operated by apparatus responsive to the speed of a train approaching the intersection.

In signaling systems of the character noted it is desirable that the highway signal be operated a substantially constant time interval before a train traveling upon the stretch of railway track reaches the intersection, regardless of the speed of the train, in order to give one using the highway adequate warning of the approaching train.

15 A signaling system of this character is described and illustrated in United States Patent No. 1,934,094, John E. Saunders, granted November 7, 1933. In this signaling system the apparatus responsive to the speed of a train approaching

20 the intersection for operating the highway signal located near the intersection comprises a timer, which includes a rotatable drum circuit controller, spring-biased to a normal position, and rotatable to an off-normal position by an

25 arrangement including an electric motor and a friction drive. When the timer is set into operation, the electric motor is energized during a predetermined time interval, thereby rotating, through the friction drive, the drum away from its normal position into an off-normal position. The electric motor is then deenergized and the drum is returned from the off-normal position to its normal position by the spring, the motor connected

30 through the friction drive to the drum serving as a brake to regulate the time interval required by the drum to return from its off-normal position to its normal position. In order that the timer may properly control the operation of the highway signal, the distance the

35 drum is rotated from its normal position into an off-normal position must be directly proportional to the time interval during which the electric motor is energized; and the time interval required by the drum to return from its off-

40 normal position to its normal position must be directly proportional to the distance between the off-normal position and the normal position. In other words, in the timer, the drum must be returned from the off-normal position to its normal position at the same speed that the drum is advanced from its normal position to the off-normal position, in order that the timer may properly control the operation of the highway signal. These factors must be maintained with- 45

5 difficult to accomplish when the relationships therebetween are effected by such variable devices as a friction drive, a spring, and an electric motor. Thus the timer in this system must be of very delicate construction and in nice adjustment in order adequately to perform its timing function. Moreover, this timer must be frequently inspected and adjusted in service.

Accordingly, it is an object of the present invention to provide in a traffic signaling system 10 of the character described, an improved control arrangement which comprises a minimum number of elements of simple and economical construction, and which is positive and completely reliable in operation.

15 It is another object of the invention to provide for use in a traffic signaling system of the character noted, improved timing apparatus which is operable positively to start the operation of the highway signal located near the intersection at substantially the same time interval before a train traveling upon the stretch of railway track reaches the intersection, regardless of the speed of the train.

20 It is a further and more specific object of the 25 invention to provide in a traffic signaling system of the character described, improved and exceedingly simple circuit arrangements in order to start the operation of the highway signal located near the intersection at substantially the same 30 time interval before a train traveling upon the stretch of railway track reaches the intersection, regardless of the speed of the train.

25 In general, the objects as above set forth are attained in accordance with the present invention by providing in a traffic signaling system of the character described, impulsing apparatus 35 adapted to transmit impulses at a substantially constant rate, means for setting the apparatus into operation when a train approaches the intersection, an impulse responsive device controlled by the apparatus, and means controlled by the device for starting the operation of the highway signal at substantially the same time interval before the train reaches the intersection, regardless of the speed of the train. More particularly, the impulse responsive device includes two 40 impulse counting mechanisms, the first of which is so connected and arranged that it counts a first number of impulses transmitted by the apparatus during the time interval required by a train approaching the intersection to traverse a given distance, and the other of which is so connected and arranged that it counts automatically 45 a second number of impulses transmitted by the 50 apparatus during the time interval required by a train approaching the intersection to traverse a given distance, and the other of which is so connected and arranged that it counts automatically 55 a second number of impulses transmitted by the

apparatus immediately following the first number of impulses transmitted by the apparatus, the second number being less by a fixed number than the first number. Also, the system includes 5 means controlled in response to the counting of the second number of impulses by the other mechanism of the device for starting the operation of the highway signal.

The novel features believed to be characteristic of the invention are set forth with particularity in the appended claims. The invention, both as to its organization and method of operation, together with further objects and advantages thereof, will best be understood by reference 10 to the following specification, taken in connection with the accompanying drawing in which the single figure is a diagrammatic illustration of a traffic signaling system having embodied therein the features of the present invention.

Referring now more particularly to the drawing, the traffic signaling system there illustrated includes a stretch of railway track 10 along which traffic normally moves from the left toward the right, as indicated by the arrow. The stretch of 15 railway track 10 includes track rails 11 and 12, which are divided by suitable insulating joints 13 to form three track sections 10A, 10B and 10C having the lengths S1, S2 and S3, respectively. The track section 10C intersects a highway 14 20 a distance S4 from the end of the adjacent track section 10B, and a suitable highway signal 15 is located at or near the intersection. The lengths of the track sections 10A, 10B and 10C are so 25 related with respect to each other and to the position of the intersection of the track section 10C and the highway 14 that the distance S1 is equal to the sum of the distances S2 and S4. The track sections 10A, 10B and 10C are provided 30 with individual track circuits including batteries 16 and track relays R20, R30 and R40, respectively.

The signaling system also includes impulsive apparatus 17, a switch device illustrated diagrammatically at 50, a relay R70 for controlling 45 the operation of the highway signal 15, circuits for controlling the operation of the impulsive apparatus 17, circuits for controlling the operation of the switch device 50, circuits for controlling the operation of the relay R70, and an arrangement including a plurality of relays R80, 50 R82, R84 and R86, operable in conjunction with the switch device 50 to control one of the circuits for controlling the operation of the relay R70.

The impulsive apparatus 17 may be of any of 55 a number of well-known types available commercially and comprises positive and negative incoming terminals 18^a, 18^b, and positive and negative outgoing terminals 19^a, 19^b. This apparatus is so connected and arranged that, when the positive terminal of battery is connected to the terminal 18^a and the negative terminal of battery is connected to the terminal 18^b, the apparatus is set into operation and transmits negative impulses from the negative terminal of 60 battery connected to the terminal 19^b over a conductor connected to the terminal 19^a. These negative impulses are of sufficient duration to operate the switch device 50 and are of any substantially constant predetermined rate desired. 65 In the present system and for purposes of illustration, it is assumed that the apparatus 17 transmits forty negative impulses per minute over a conductor connected to the terminal 19^a, and that this impulsive rate is substantially constant. 70

The switch device 50 is a circuit controlling

device of the general form disclosed in United States Patent No. 2,057,911, Herbert F. Obergfell, granted October 20, 1936. More specifically, this device is of the improved construction disclosed and claimed in the copending application of Herbert F. Obergfell, Serial No. 192,960 filed February 28, 1938 now U. S. Patent No. 2,184,101, granted December 19, 1939. In brief, the device 50 comprises two relatively rotatable elements 51 and 52, the element 51 comprising a contact set including three pairs of contact members 53, 54 and 55, and the element 52 comprising a support carrying three insulating members 56, 57 and 58. The element 51 is rotated step-by-step in a predetermined direction by an impulse responsive mechanism 59 including a motor magnet MM60 and a suitable pawl and ratchet wheel driving mechanism indicated at 61. The element 52 is rotated step-by-step in the same direction as the element 51 by an impulse responsive mechanism 62 including a motor magnet MM63 and a suitable pawl and ratchet wheel driving mechanism indicated at 64. The ratchet wheels included in these mechanisms are provided with the same number of equally spaced-apart teeth, 15 and for purposes of illustration it is assumed that each of the ratchet wheels is provided with fifty equally spaced-apart teeth disposed about its periphery. The device 50 and the apparatus 17 are so connected and arranged that the mechanisms 59 and 62 constitute, respectively, means for counting a first number of impulses transmitted by the apparatus, and means for counting a second number of impulses transmitted by the apparatus; the element 51 being rotated one step 20 by the mechanism 59 upon each impulse transmitted by the apparatus 17 and received by the motor magnet MM60, and the element 52 being rotated one step by the mechanism 62 upon each impulse transmitted by the apparatus 17 and 25 received by the motor magnet MM63. The insulating members 56, 57 and 58 are individually associated with the pairs of contact members 53, 54 and 55, respectively; the contact members of each pair being biased toward each other or 30 into closed contact position, and each insulating member being adapted to be moved between the contact members of the associated pair, thereby 35 to move the associated pair away from each other or into open contact position. 40

When the switch device 50 is in a non-operated condition, each of the elements 51 and 52 occupies an initial or start position. When operation of the device 50 is initiated, the motor magnet MM60 is first repeatedly energized to rotate the element 51 a predetermined number of steps in a given direction from its start position, thereby causing the pairs of contact members to be moved in a predetermined order from one contact position to the other. Thereafter, the motor magnet MM63 is repeatedly energized to rotate the element 52 a predetermined number of steps in the same direction from its start position, thereby causing the pairs of contact members to be moved in a predetermined order from the other contact position back to the one contact position. More specifically, the elements 51 and 52 are so constructed and arranged that, when these elements occupy their initial or start positions, the insulating member 56 is disposed forty-nine steps ahead of the associated pair of contact members 53, the insulating member 57 is disposed between the associated pair of contact members 54, and the rear end of the insulating member 58 is disposed between the associated 55 60 65 70 75

pair of contact members 55. Thus, in the start positions of the elements 51 and 52, the pair of contact members 53 occupies its closed contact position, and the pairs of contact members 54 and 55 occupy their open contact positions. The insulating members 56 and 57 are so dimensioned with respect to the distance rotated by the associated pairs of contact members 53 and 54 upon a single step of the element 51 that the insulating member 57 is removed from between the associated pair of contact members 54 upon the first step of the element 51 from its start position, and that the insulating member 56, when disposed between the associated pair of contact members 53, is removed from therebetween upon the first step of the element 52 from its start position. The insulating member 58 is so dimensioned with respect to the distance rotated by the element 51 upon a single step thereof that this insulating member remains in its position disposed between the associated pair of contact members 55 during a predetermined number of steps of the element 51 from its start position. For purposes of illustration it is assumed that the insulating member 58 is so dimensioned with respect to the distance rotated by the element 51 upon a single step thereof that this insulating member remains in its position disposed between the associated pair of contact members 55 during the first thirteen steps of the element 51 from its start position. Thus it will be apparent that in the first through the thirteenth positions of the element 51 from its start position, the pairs of contact members 53 and 54 occupy their closed contact positions and the pair of contact members 55 occupies its open contact position. When the element 51 is advanced into its fourteenth position from its start position, the pair of contact members 55 is moved into its closed contact position. In the fourteenth through the forty-eighth positions of the element 51 from its start position, the pairs of contact members 53, 54 and 55 occupy their closed contact positions. If the element 51 is advanced into its forty-ninth position from its start position, which position is only one step behind its start position, the insulating member 56 is brought between the associated pair of contact members 53, thereby moving this pair of contact members into its open contact position.

The element 52 is then rotated step-by-step from its start position, and the pairs of contact members 53, 54 and 55 remain in closed contact positions until the element 52 is advanced to a position disposed thirteen steps behind the position of the element 51, at which time the pair of contact members 55 is moved to its open contact position. The pairs of contact members 53 and 54 remain in their closed contact positions, and the pair of contact members 55 remains in its open contact position until the element 52 is advanced into a position corresponding to the position of the element 51, at which time the pair of contact members 54 is moved to its open contact position. As will be more fully described subsequently, the pair of contact members 53 is included in the circuit for energizing the motor magnet MM60 of the mechanism 59, which mechanism rotates the element 51 from its start position. The pair of contact members 53 is moved to its open contact position when the element 51 is advanced into its forty-ninth position from its start position, causing the operation of the motor magnet MM60 to be positively arrested at this time, thereby

preventing the element 51 from being advanced into its fiftieth or start position. The pair of contact members 54 is included in an operating circuit for the impulsing apparatus 17, and the pair of contact members 55 is included in a circuit for energizing the relay R70, which latter relay controls the operation of the highway signal 15.

Referring now to the operation of the signaling system, when the stretch of railway track 10 is clear of trains, the track circuits individual to the track sections 10A, 10B and 10C are completed, thereby energizing the track relays R20, R30 and R40 from the batteries 16. The operated relay R20 holds interrupted, at its armature RA21, a point in a primary circuit for operating the impulsing apparatus 17, this circuit extending, when completed, from the positive terminal of a battery, not shown, by way of the armature RA31 of the relay R30, RA21, a conductor C90, the terminal 18^a of the apparatus 17, through the apparatus 17, and the terminal 18^b of the apparatus 17 to the negative terminal of the battery. The operated relays R30 and R40 hold completed a first circuit for energizing the relay R70, this circuit extending from the positive terminal of battery by way of the armature RA32 of the relay R30, the armature RA41 of the relay R40, and the winding of R70 to the negative terminal of battery. The operated relay R70 holds interrupted at its armature RA71 an obvious operating circuit for the highway signal 15, thereby rendering the highway signal 15 inoperative at this time.

When a train approaching the intersection of the stretch of railway track 10 and the highway 14 enters the track section 10A, the track relay R20 is short-circuited, causing this relay to restore and complete at RA21 the above-traced primary circuit for operating the impulsing apparatus 17. When the impulsing apparatus 17 is set into operation, it transmits forty negative impulses per minute from the negative terminal of battery connected to the terminal 19^b over the conductor C91 connected to the terminal 19^a. At this time the conductor C91 is included in a circuit for energizing the motor magnet MM60 of the mechanism 59 included in the switch device 50, this circuit extending from the conductor C91 by way of the armature RA33 of the relay R30, the armature RA22 and its associated contact RC23 of the relay R20, a conductor C92, the winding of the motor magnet MM60, a conductor C93, and the pair of contact members 53 to the positive terminal of battery. As the pair of contact members 53 occupies its closed position at this time, the motor magnet MM60 is energized. The motor magnet MM60 is operated upon each impulse transmitted by the impulsing apparatus 17, causing the element 51 to be advanced step-by-step a predetermined number of steps from its start position. When the element 51 is advanced into its first position P1 from its start position P50, the pair of contact members 54 is moved into its closed contact position, thereby completing an auxiliary circuit for operating the impulsing apparatus 17, which is independent of the above-traced primary operating circuit for the impulsing apparatus 17, this auxiliary circuit extending from the positive terminal of battery by way of the pair of contact members 54, a conductor C94, the terminal 18^a of the apparatus 17, through the apparatus 17, and the terminal 18^b of the apparatus 17 to the negative terminal of battery. 75

Upon the first operation of the motor magnet MM60, a circuit is completed for energizing the relay R80, this circuit extending from the positive terminal of battery by way of the armature RA60, a conductor C95, and the winding of R80 to the negative terminal of battery. This energizing circuit is completed at RA60 each time the motor magnet MM60 is operated. As the relay R80 is of the slow-to-release type, the same does not restore between the repeated operations of the motor magnet MM60. Upon operating, the relay R80 completes at its armature RA81 an obvious circuit for energizing the relay R82; the latter relay operates and completes at its armature RA83 an obvious circuit for energizing the relay R84; the latter relay operates and completes at its armature RA85 an obvious circuit for energizing the relay R86; and the latter relay operates and prepares at its armature RA87 a point in a second circuit for energizing the relay R70, this latter circuit extending, when completed, from the positive terminal of battery by way of RA87, a conductor C96, the pair of contact members 55, a conductor C97, RA41, and the winding of R70 to the negative terminal of battery. At this time the above-traced second circuit for energizing the relay R70 is held interrupted at the pair of contact members 55. The pairs of contact members 53 and 54 remain in their closed contact positions and the pair of contact members 55 remains in its open contact position, while the element 51 is advanced from its first position P1 and until the element 51 is advanced into its fourteenth position P14. At this time the pair of contact members 55 is moved into closed contact position, thereby completing the above-traced second circuit for energizing the relay R70.

The element 51 is advanced step-by-step from its start position by the mechanism 59 one step for each impulse transmitted by the impulsive apparatus 17 and received by the motor magnet MM60, until the train traveling upon the stretch of railway track 10 enters the track section 10B. When the train enters the track section 10B, the track relay R30 is short-circuited, causing this relay to restore. Upon restoring, the relay R30 interrupts at RA31 the primary operating or start circuit for the impulsive apparatus 17. The impulsive apparatus continues to operate, however, as the auxiliary operating circuit for the same is completed. The relay R30 also interrupts at RA32 the first circuit for energizing the relay R70. However, the relay R70 remains operated at this time as the second circuit for energizing the same is completed. Also, the relay R30 interrupts at RA33 the above-traced circuit for energizing the motor magnet MM60 of the mechanism 59 included in the switch device 50, and completes at its armature RA34 a circuit for energizing the motor magnet MM63 of the mechanism 62 included in the switch device 50, the latter circuit extending from the negative terminal of battery connected to the terminal 19b of the impulsive apparatus 17, through the apparatus 17, the terminal 19a of the apparatus 17, C91, RA34, a conductor C98, and the winding of the motor magnet MM63 to the positive terminal of battery. The motor magnet MM63 is operated upon each impulse transmitted by the impulsive apparatus 17, causing the element 52 to be advanced step-by-step a predetermined number of steps from its start position. As the element 52 is advanced from its start position,

the pairs of contact members 53, 54 and 55 remain in their closed positions until the element 52 is advanced to a position disposed thirteen steps behind the position of the element 51, at which time the insulating member 58 is brought 5 between the pair of contact members 55, thereby moving this pair of contact members to its open contact position to interrupt the second circuit for energizing the relay R70. The relay R70 then restores as the first circuit for energizing 10 the same is interrupted at the armature RA32 of the restored relay R30. Upon restoring, the relay R70 completes at RA71 the above-traced circuit for operating the highway signal 15, causing this signal to be set into operation to give 15 one using the highway warning of the approaching train.

The element 52 is advanced step-by-step from its start position until it occupies a position corresponding to the position of the element 51, 20 at which time the insulating member 57 is brought between the pair of contact members 54, thereby moving this pair of contact members to its open contact position to interrupt the above-traced auxiliary circuit for continuing 25 the operation of the impulsive apparatus 17. The impulsive apparatus 17 is then returned to a non-operated condition, and the switch device 50 is in a condition wherein the elements 51 and 52 occupy corresponding new positions disposed 30 from their original start positions. These corresponding new positions constitute start positions for the elements 51 and 52 during the next cycle of operation of the switch device 50.

From the foregoing it will be apparent that 35 the element 51 of the switch device 50 is advanced a first number of steps from its start position, which number depends upon the number of impulses transmitted by the apparatus 17 during the time interval required by the train 40 approaching the intersection to traverse the length of the track section 10A. The time required by the train to traverse the length of the track section 10A is inversely proportional to the speed of the approaching train. Thus, 45 the number of steps the element 51 of the switch device 50 is advanced from its start position is inversely proportional to the speed of the approaching train. Moreover, as previously explained, when the approaching train enters the 50 track section 10B, further movement of the element 51 is arrested and movement of the element 52 is initiated. The element 52 is then advanced this first number of steps from its start position, at which time further movement 55 thereof is arrested. As the impulsive apparatus 17 causes the elements 51 and 52 to be advanced step-by-step from their start positions at the same rate, the elements 51 and 52 will be moved the same distance during equal time intervals. 60 As previously pointed out, the element 51 is moved step-by-step during a time interval corresponding to the time interval required by the approaching train to traverse the length of the track section 10A. Accordingly, the element 65 52 is moved step-by-step during a time interval corresponding to the time interval required by the approaching train to traverse the length of the track section 10A. As movement of the element 52 is initiated when the approaching train 70 enters the track section 10B, the approaching train will travel a distance from the beginning of the track section 10B equal to the length of the track section 10A during the interval of time the element 52 is being moved step-by-step. 75

As the length of the track section 10A corresponds to the distance S1, and the distance S1 is equal to the sum of the distances S2 and S4, it follows that the train will reach the intersection at the same time the element 52 is moved the first number of steps mentioned. As previously pointed out, the highway signal 15 is operated when the element 52 is advanced to a position thirteen steps behind the position of the element 51. Thus, the highway signal 15 is operated a time interval before the train reaches the intersection corresponding to the time interval required by the element 52 to be advanced thirteen steps, which last-mentioned time interval corresponds to thirteen-fortieths of a minute or nineteen and one-half seconds. The highway signal 15 will be operated this nineteen and one-half seconds before the train reaches the intersection, regardless of the speed of the train, assuming the speed of the train does not vary during the travel of the train in the stretch of railway track 10 over the distances S1, S2 and S4.

For example, assuming that the train approaching the intersection is traveling at a relatively low speed such that the train occupies the track section 10A for sixty seconds, the element 51 of the switch device 50 will be advanced forty steps from its start position during this time interval. When the train enters the track section 10B the element 52 of the switch device 50 is advanced automatically from its start position. When the element 52 is advanced twenty-seven steps from its start position, the pair of contact members 55 is moved into its open contact position, thereby causing operation of the highway signal 15, as previously explained. Thus the highway signal 15 is operated thirteen steps before the element 52 is advanced to the position 40 of the element 51, which corresponds to a time interval of nineteen and one-half seconds before the train reaches the intersection. Similarly, if the train approaching the intersection is traveling at a relatively high speed such that the train occupies the track section 10A for thirty seconds, the element 51 will be advanced twenty steps from its start position during this time interval. When the train enters the track section 10B the element 52 is advanced automatically from its start position. When the element 52 is advanced seven steps from its start position the pair of contact members 55 is moved into its open contact position, thereby causing operation of the highway signal 15, as previously explained. Thus the highway signal 15 is operated thirteen steps before the element 52 is advanced to the position of the element 51, which corresponds to a time interval of nineteen and one-half seconds before the train reaches the intersection.

60 During the operation of the system, should a train approaching the intersection be stopped in the track section 10A or travel through the track section 10A at an exceedingly slow speed such that the train occupies the track section 10A for a time interval exceeding seventy-three and one-half seconds, the element 51 of the switch device 50 is advanced forty-nine steps from its start position, at which time the pair of contact members 53 is moved into its open contact position, thereby interrupting the energizing circuit of the motor magnet MM60. This arrangement prevents the element 51 from being advanced from its start position forwardly fifty steps into a position, which is the same as its start position. 75 In this case, when the train enters the track

section 10B the element 52 is advanced thirty-six steps before the highway signal 15 is operated, as previously explained. Accordingly, in this case, the highway signal 15 is operated a time interval somewhat greater than nineteen and one-half 5 seconds before the train reaches the intersection. From the foregoing it will be apparent that during normal operation of the system the highway signal 15 is operated nineteen and one-half seconds before the train reaches the intersection, 10 regardless of the speed of the train.

As a train traveling upon the stretch of railway track 10 successively clears the track sections 10A, 10B and 10C, the track relays R20, R30 and R40 are successively operated to their 15 normal positions. Upon operating the track relay R20 interrupts at its armature RA21 a further point in the primary circuit for operating the impulsive apparatus 17, and interrupts at its armature RA22 and its associated contact RC23 a 20 further point in the circuit for energizing the motor magnet MM60. Upon operating, the track relay R30 prepares at its armature RA31 a point in the primary circuit for operating the impulsive apparatus 17, prepares at its armature RA32 25 a point in the circuit for energizing the relay R10, prepares at its armature RA33 a point in the circuit for energizing the motor magnet MM60, and interrupts at its armature RA34 a 30 further point in the circuit for energizing the motor magnet MM63. Upon operating, the track relay R40 completes at its armature RA41 the first circuit for energizing the relay R70, causing operation of the latter relay. Upon operating, the relay R70 interrupts at its armature RA71 35 the operating circuit for the highway signal 15, thereby rendering the highway signal inoperative.

The relays R80, R82, R84 and R86, and the circuits for energizing these relays, constitute a 40 safety arrangement for operating the highway signal 15 in the event the switch device 50 does not function properly. For example, during normal operation of the system, when the train approaching the intersection enters the track section 10A, the circuit for energizing the motor magnet MM60 is completed at the armature RA22 of the track relay R20; when the element 51 is advanced one step from its start position the auxiliary circuit for operating the impulsive apparatus 17 is completed at the pair of contact members 54; and when the element 51 is advanced thirteen steps from its start position the second circuit for energizing the relay R10 is completed at the pair of contact members 55. 55 If, due to some defect in the switch device 50, the motor magnet MM60 is not operated, the circuit for energizing the relay R20 is not completed. Thus, the relays R80, R82, R84 and R86 are not operated, as previously explained. Consequently, 60 the second circuit for energizing the relay R70 is interrupted at the armature RA87 of the relay R86. Accordingly, when the train approaching the intersection enters the track section 10B, thereby causing the first circuit for energizing 65 the relay R70 to be interrupted at the armature RA32 of the track relay R30, the relay R70 is restored to cause the operation of the highway signal 15 a time interval appreciably greater than nineteen and one-half seconds before the train 70 enters the intersection. Likewise, due to some defect in the switch device 50, if the motor magnet MM63 is not operated when the train approaching the intersection enters the track section 10B, a branch circuit for energizing the 75

relay R80 is not completed, this circuit extending, when completed, from the positive terminal of battery by way of the armature RA63 of the motor magnet MM63, a conductor C99, and the 5 winding of R80 to the negative terminal of battery. Accordingly, when the train enters the track section 10B, thereby causing the circuit for energizing the motor magnet MM60 to be interrupted at the armature RA33 of the track relay 10 R30, and causing the circuit for energizing the motor magnet MM63 to be completed at the armature RA34 of the track relay R30, the circuit extending by way of the armature RA60 of the motor magnet MM60 for energizing the relay R80 15 is interrupted at RA60 and the branch circuit for energizing the relay R80 is not completed at RA63 of the motor magnet MM63 due to the failure of the motor magnet MM63 to operate. Accordingly, the relay R80, being of the slow-to-20 release type, restores shortly after the train enters the track section 10B. The relays R82, R84 and R86, being of the slow-to-release type, successively restore, in the order named, short intervals of time after the restoration of the relay 25 R80. When the relay R86 restores, the second circuit for energizing the relay R70 is interrupted at RA87 of the relay R86, thereby causing operation of the highway signal 15 a time interval somewhat greater than nineteen and one-half 30 seconds before the train enters the intersection.

The track relay R40 constitutes a check relay and part of an emergency operating arrangement for the highway signal 15. In this connection it will be observed that, when a train approaching the intersection enters the track section 10C, the track relay R40 is short-circuited, causing the same to restore. Upon restoring, the relay R40 interrupts at its armature RA41 a point in both the first and the second circuits 35 for energizing the relay R70 independently of the positions of the track relay R30 and the switch device 50. The relay R70 then restores and completes at its armature RA71 the operating 40 circuit for the highway signal 15. This arrangement provides for emergency operation of the highway signal 15 in response to the position of the train approaching the intersection, and without regard to its speed and the operations of the previously described elements of the 45 system.

During the operation of the system it is possible that a train approaching the intersection might enter the track section 10A, stop therein, and then back out of the track section 10A without reaching the intersection. In this case, when the train enters the track section 10A and stops therein, the element 51 of the switch device 50 is advanced from its start position forty-nine steps, further movement thereof being arrested as previously explained. When the train then backs out of the track section 10A, the track relay R20 is again operated. Upon operating, the track relay R20 completes at its armature RA22 and its associated contact RC24 an auxiliary circuit 60 for energizing the motor magnet MM63, this circuit extending from the negative terminal of battery connected to the terminal 19^b of the apparatus 17, through the apparatus 17, the terminal 19^a of the apparatus 17, the conductor C91, the armature RA33 of the track relay R30, the armature RA22 and its associated contact RC24 of the track relay R20, the conductor C98, and the winding of the motor magnet MM63 to the positive terminal of battery. The element 70 75 52 of the switch device 50 is then advanced forty-

nine steps from its start position, whereupon the pair of contact members 57 is moved to its open contact position, thereby interrupting the auxiliary operating circuit for the impulsing apparatus 17. The elements of the system then occupy their initial positions and the system is in a non-operated condition. 5

From the foregoing description of the traffic signaling system it will be apparent that the highway signal located near the intersection of 10 the stretch of railway track and the highway is operated in a positive manner, by exceedingly simple circuit arrangements, a predetermined time interval before a train traveling upon the stretch of railway track reaches the intersection, 15 regardless of the speed of the train.

While there has been described what is at present considered to be the preferred embodiment of the invention, it will be understood that various modifications may be made therein without departing from the invention, and it is intended in the appended claims to cover all such modifications as fall within the true spirit and scope of the invention. 20

What is claimed is: 25

1. In a traffic signaling system including a stretch of railway track intersected by a highway, and a highway crossing signal located near the intersection; the combination comprising an impulsing apparatus adapted to transmit impulses at a substantially constant rate, means for counting a first number of impulses transmitted by said apparatus during the time interval required by a train approaching the intersection to traverse a given distance and then for 30 counting automatically a second number of impulses transmitted by said apparatus, said second number being less by a fixed number than said first number, and means controlled in response to the counting of said second number of 35 impulses by said last-mentioned means for starting the operation of said highway signal. 40

2. In a traffic signaling system including a stretch of railway track intersected by a highway, and a highway crossing signal located near 45 the intersection; the combination comprising an impulsing apparatus adapted to transmit impulses at a substantially constant rate, means for counting a first number of impulses transmitted by said apparatus depending upon the 50 speed of a train approaching the intersection and then for counting automatically a second number of impulses transmitted by said apparatus, said first number varying inversely as the speed of the train and said second number being less by a fixed number than said first number, and means controlled in response to the 55 counting of said second number of impulses by said last-mentioned means for starting the operation of said highway signal. 60

3. In a traffic signaling system including a stretch of railway track intersected by a highway, and a highway crossing signal located near the intersection; the combination comprising an impulsing apparatus adapted to transmit impulses at a substantially constant rate, a device including two impulse responsive mechanisms adapted selectively to be actuated upon each impulse transmitted by said apparatus, said apparatus and said device being so connected and 65 arranged that one of said mechanisms is actuated by said apparatus a first number of times depending upon the time interval required by a train approaching the intersection to traverse a given distance and then the other of said mech- 70 75 75

anisms is actuated a second number of times automatically, said second number being less by a fixed number than said first number, and means controlled by the actuation of said other mechanism said second number of times for starting the operation of said highway signal.

4. In a traffic signaling system including a stretch of railway track intersected by a highway, and a highway crossing signal located near the intersection; the combination comprising an impulsing apparatus adapted to transmit impulses at a substantially constant rate, a device including two impulse responsive mechanisms adapted selectively to be actuated upon each impulse transmitted by said apparatus, said apparatus and said device being so connected and arranged that one of said mechanisms is actuated by said apparatus a first number of times depending upon the time interval required by a train approaching the intersection to traverse a given distance and then the other of said mechanisms is actuated said first number of times automatically, and means controlled by the actuation of said other mechanism a second number of times less by a fixed number of times than said first number of times for starting the operation of said highway signal.

5. In a traffic signaling system including a stretch of railway track intersected by a highway, and a highway crossing signal located near the intersection; the combination comprising an impulsing apparatus adapted to transmit impulses at a substantially constant rate, a device including two impulse responsive mechanisms, said apparatus being connected and arranged to actuate a selected one of said mechanisms upon each impulse transmitted thereby, means for connecting said apparatus to one of said mechanisms when a train approaches the intersection, said one mechanism being actuated by said apparatus a first number of times depending upon the time interval required by the train approaching the intersection to traverse a given distance, means responsive to the actuation of said one mechanism a predetermined number of times for arresting further actuation of said one mechanism, means responsive to the travel of the train said given distance for connecting said apparatus to the other of said mechanisms, means responsive to the actuation of said other mechanism said first number of times for arresting further actuation of said other mechanism, and means controlled by the actuation of said other mechanism a second number of times less by a fixed number of times than said first number of times for starting the operation of said highway signal.

6. In a traffic signaling system including a stretch of railway track intersected by a highway, and a highway crossing signal located near the intersection; the combination comprising an impulsing apparatus adapted to transmit impulses at a substantially constant rate, two impulse counting mechanisms, means including a first motor operable to actuate one of said counting mechanisms, means including a second motor operable to actuate the other of said counting mechanisms, said apparatus being connected and arranged to actuate a selected one of said motors upon each impulse transmitted thereby, means for connecting said apparatus to said first motor when a train approaches the intersection, said one counting mechanism being actuated by said first motor a first number of times depending upon the time interval required by the

train approaching the intersection to traverse a given distance, means responsive to the actuation of said one counting mechanism a predetermined number of times for arresting the operation of said first motor, means responsive to the travel of the train said given distance for connecting said apparatus to said second motor, means responsive to the actuation of said other mechanism said first number of times for arresting the operation of said second motor, and means controlled by the actuation of said other mechanism a second number of times less by a fixed number of times than said first number of times for starting the operation of said highway signal.

7. In a traffic signaling system including a stretch of railway track intersected by a highway, and a highway crossing signal located near the intersection; the combination comprising an impulsing apparatus adapted to transmit impulses at a substantially constant rate, a device including two impulse responsive mechanisms adapted selectively to be actuated upon each impulse transmitted by said apparatus, said apparatus and said device being so connected and arranged that one of said mechanisms is actuated by said apparatus a first number of times depending upon the speed of a train approaching the intersection and then the other of said mechanisms is actuated a second number of times automatically, said first number varying inversely as the speed of the train and said second number being less by a fixed number than said first number, means controlled by the actuation of said other mechanism said second number of times for starting the operation of said highway signal, and independent means for starting the operation of said highway signal.

8. In a traffic signaling system including a stretch of railway track intersected by a highway, and a highway crossing signal located near the intersection; the combination comprising an impulsing apparatus adapted to transmit impulses at a substantially constant rate, a device including two impulse responsive mechanisms, said apparatus being connected and arranged to actuate a selected one of said mechanisms upon each impulse transmitted thereby, means for setting said apparatus into operation when a train approaches the intersection and for connecting said apparatus to one of said mechanisms, said one mechanism being actuated by said apparatus a first number of times depending upon the time interval required by the train approaching the intersection to traverse a given distance, means responsive to the travel of the train said given distance for connecting said apparatus to the other of said mechanisms, said other mechanism being actuated by said apparatus a second number of times automatically, said second number being less by a fixed number than said first number, and means controlled by the actuation of said other mechanism said second number of times for starting the operation of said highway signal.

9. In a traffic signaling system including a stretch of railway track including a plurality of track sections and intersected by a highway, and a highway crossing signal located near the intersection; the combination comprising an impulsing apparatus adapted to transmit impulses at a substantially constant rate, means for setting said apparatus into operation when a train approaching the intersection enters a first of said track sections, a device including two im-

- pulse responsive mechanisms adapted selectively to be actuated upon each impulse transmitted by said apparatus, said apparatus and said device being so connected and arranged that one of 5 said mechanisms is actuated by said apparatus a first number of times depending upon the time interval required by the train to traverse said first track section and then the other of said mechanisms is actuated a second number of 10 times automatically when the train enters a second of said track sections, said second number being less by a fixed number than said first number, means controlled by the actuation of said other mechanism said second number of 15 times for starting the operation of said highway signal, and means operated when the train enters a third of said track sections for starting independently the operation of said highway signal.
- 20 10. In a traffic signaling system including a stretch of railway track intersected by a highway, and a highway crossing signal located near the intersection; the combination comprising a relay operable to one position to start the operation 25 of said highway signal, a normally closed first energizing circuit and a normally open second energizing circuit for said relay, an impulsive apparatus adapted to transmit impulses at a substantially constant rate, a device including two impulse responsive mechanisms, said apparatus being connected and arranged to actuate a selected one of said mechanisms upon each impulse transmitted thereby, means for setting said apparatus into operation 30 35 when a train approaches the intersection and for connecting said apparatus to one of said mechanisms, said one mechanism being actuated by said apparatus a first number of times depending upon the time interval required by the train 40 approaching the intersection to traverse a given distance, means controlled by said first mechanism for completing said second energizing circuit, means responsive to the travel of the train said given distance for connecting said apparatus to the other of said mechanisms and for 45 interrupting said first energizing circuit, said other mechanism being actuated by said apparatus a second number of times automatically, said second number being less by a fixed number 50 than said first number, and means controlled by the actuation of said other mechanism said second number of times for interrupting said second energizing circuit, thereby causing said relay to be operated to said one position.
- 55 11. In combination, time measuring means including an impulsive apparatus adapted to transmit impulses at a substantially constant rate, an impulse counter, control means for causing 60 said impulse counter to count a first number of impulses transmitted by said impulsive apparatus during the lapsed time of an event and then at the expiration of said event to count automatically a second number of impulses 65 transmitted by said impulsive apparatus, said second number being less by a fixed number than said first number, and means controlled in response to the counting of said second number of impulses for controlling the operation of an associated device.
- 70 12. In combination, time measuring means including an impulsive apparatus adapted to transmit impulses at a substantially constant rate, an impulse counter, control means for initiating 75 operation of said impulse counter at the be-

ginning of an event and for causing said impulse counter to count a first number of impulses transmitted by said impulsive apparatus during the lapsed time of said event and then at the expiration of said event to count automatically a further number of impulses transmitted by said impulsive apparatus, said further number being equal to said first number, means responsive to the counting of said further number of impulses for arresting operation 10 of said impulse counter, and means controlled in response to the counting of another number of impulses for controlling the operation of an associated device, said other number being less by a fixed number than said further number. 15

13. In combination, time measuring means including an impulsive apparatus adapted to transmit impulses at a substantially constant rate, an impulse counter, control means for operating 20 said impulse counter to count a first number of impulses transmitted by said impulsive apparatus during the lapsed time of an event, means for arresting the counting operation of said impulse counter after a predetermined first number of impulses have been counted in the event 25 that the lapsed time of said event exceeds a predetermined time interval, control means for operating said impulse counter to count automatically at the expiration of said event a second number of impulses transmitted by said impulsive apparatus, said second number being less by a fixed number than said first number, and means controlled in response to the counting of 30 said second number of impulses for controlling the operation of an associated device. 35

14. In combination, time measuring means including an impulsive apparatus adapted to transmit impulses at a substantially constant rate, a first and a second member independently movable step by step in the same direction along 40 a common path, said members having a synchronous position with respect to each other which may occur at any point along said path, a circuit controlling contact operated jointly by said members to different predetermined circuit 45 control positions determined by the different relative positions of said members with respect to each other, motor actuated means operatively connected to said members, and control means effective to energize periodically from said impulsive apparatus said motor actuated means to move first member step by step away from the synchronous position during the lapsed time of an event and then at the expiration of said event to move said second member step by step until 55 the synchronous position is again established, said circuit controlling contact being adapted to govern an associated operating circuit.

15. In combination, time measuring means including an impulsive apparatus adapted to 60 transmit impulses at a substantially constant rate, a first and a second member independently movable step by step in the same direction along a common path, said members having a synchronous position with respect to each other 65 which may occur at any point along said path, a circuit controlling contact operated jointly by said members to different predetermined circuit control positions determined by the different relative positions of said members with respect to each other, motor actuated means operatively connected to said members, control means effective to energize periodically from said impulsive apparatus said motor actuated means to move said first member step by step away from 70 75

the synchronous position during the lapsed time of an event, means for arresting the movement of said first member after said first member has been moved a predetermined number of steps 5 in the event that the lapsed time of said event exceeds a predetermined time interval, and control means effective to energize periodically from said impulsing apparatus at the expiration of said event said motor actuated means to move 10 said second member step by step until the synchronous position is again established, said circuit controlling contact being adapted to govern an associated operating circuit.

16. In combination, time measuring means including an impulsing apparatus adapted to transmit impulses at a substantially constant rate, a first and a second member independently movable step by step in the same direction along a common path, said members having a synchronous 15 position with respect to each other which may occur at any point along said path, a circuit controlling contact operated jointly by said members to different predetermined circuit control positions determined by the different relative 20 positions of said members with respect to each other, motor actuated means operatively connected to said members, and control means effective to energize periodically from said impulsing apparatus said motor actuated means 25 to move said first member step by step away from the synchronous position during the lapsed time required by a train approaching the intersection to traverse a given distance and then after the train has traversed said given distance to move said second member step by step until the synchronous 30 position is again established, and a circuit including said circuit controlling contact for controlling the operation of said highway signal.

17. In combination, time measuring means including an impulsing apparatus adapted to transmit impulses at a substantially constant rate, a first and a second member independently rotatable step by step in the same direction about a common axis, said members having a synchronous 35 position with respect to each other which may occur at any angular position, a pair of contacts operated jointly by said members and made to engage when said first member is rotated a predetermined number of steps in advance of the synchronous position, a first 40 motor magnet effective when periodically energized to rotate said first member step by step, a second motor magnet effective when periodically energized to rotate said second member step by step, and control means effective to energize periodically from said impulsing apparatus said first motor magnet to rotate said first member during the lapsed time of an event to engage said pair of contacts and then to stop said first motor and to energize periodically from 45 said impulsing apparatus said second motor magnet to rotate said second member until the synchronous position is reached to disengage said pair of contacts, said pair of contacts being adapted to govern an associated operating circuit.

18. In a traffic signaling system including a stretch of railway track intersected by a highway, and a highway crossing signal located near the intersection; the combination comprising an 50 impulsing apparatus adapted to transmit impulses at a substantially constant rate, a first and a second member independently movable step by step in the same direction along a common path, said members having a synchronous 55 position with respect to each other which may

occur at any point along said path, a circuit controlling contact operated jointly by said members to different predetermined circuit control positions determined by the different relative 60 positions of said members with respect to each other, motor actuated means operatively connected to said members, control means effective to energize periodically from said impulsing apparatus said motor actuated means to move said first member step by step away from the synchronous position during the lapsed time required by a train approaching the intersection to traverse a given distance and then after the train has traversed said given distance to move said second member step by step until the synchronous 65 position is again established, and a circuit including said circuit controlling contact for controlling the operation of said highway signal.

19. In combination, a time measuring means including a first and a second member independently rotatable in the same direction about a common axis, said members having a synchronous position with respect to each other which may occur at any angular position, a pair of contacts jointly operated by said members to different predetermined circuit control positions determined by the different relative positions of said members with respect to each other and made to engage when said first member is rotated a predetermined distance ahead of the synchronous position, a first motor effective when energized to rotate said first member, a second motor effective when energized to rotate said second member, and control means effective to energize said first motor to rotate said first member during the lapsed time of an event to engage said pair of contacts and then to energize said second motor to rotate said second member until the synchronous position is reached to disengage said pair of contacts, said pair of contacts being adapted to be serially included in an associated operating circuit.

20. In a traffic signaling system including a stretch of railway track formed into a first and a second track section which a train normally travels in the order named and which are each provided with a track circuit including a track relay; the combination comprising a first motor actuated timing unit including a first member rotatable about an axis in a given direction, a second motor actuated timing unit including a second member rotatable about the same axis in said given direction, said first and second members having a synchronous position with respect to each other which may occur at any angular position, a circuit controlling contact operated by said first member when the member is rotated a predetermined distance away from the synchronous position, a first control circuit including a back contact of the track relay of the first section and a front contact of the track relay of the second section to energize the motor of said first unit for rotating said first member during the time a train is advancing through said first section, a second control circuit including a back contact of the track relay of the second section to energize the motor of said second unit for rotating said second member until the synchronous position is reached, and a signaling circuit including said circuit controlling contact.

21. In a traffic signaling system including a stretch of railway track intersected by a highway, and a highway crossing signal located near

the intersection; the combination comprising a time measuring means including a first and a second member each rotatable in the same direction about a common axis, said members having a synchronous position with respect to each other which may occur at any angular position, a pair of cooperating contacts operated jointly by said first and second members and made to engage when said first member is advanced a predetermined distance from the synchronous position ahead of said second member, an operating circuit adapted to be interrupted to set the signal into operation when a train approaching the intersection reaches a fixed point, a con-

trol circuit including said pair of contacts and adapted to render the interruption of said operating circuit ineffective to operate the signal when said pair of contacts engages, a first motor actuated device for rotating said first member to engage said pair of contacts and effectively energized during the time it takes a train to travel a given distance preceding the fixed point, and a second motor actuated device for rotating said second member to disengage said pair of contacts and effectively energized when the train reaches the fixed point. 5 10

HARRY E. HERSHHEY.

CERTIFICATE OF CORRECTION.

Patent No. 2,231,671.

February 11, 1941.

HARRY E. HERSHEY.

It is hereby certified that error appears in the printed specification of the above numbered patent requiring correction as follows: Page 7, first column, line 72, claim 6, for "tran" read --train--; page 8, second column, line 52, claim 14, after the word "move" insert --said--; and that the said Letters Patent should be read with this correction therein that the same may conform to the record of the case in the Patent Office.

Signed and sealed this 18th day of March, A. D. 1941.

Henry Van Arsdale,

(Seal)

Acting Commissioner of Patents.
